Patented June 20, 1922.

INVENTOR.

Antoine L. Girard,

BY

William E. Baffs

ATTORNEY.

UNITED STATES PATENT OFFICE.

ANTOINE L. GIRARD, OF STERLING JUNCTION, MASSACHUSETTS.

NOISEMAKER.

1,419,923.

Specification of Letters Patent. Patented June 20, 1922.

Application filed November 22, 1920. Serial No. 425,747.

To all whom it may concern:

Be it known that I, ANTOINE L. GIRARD, a citizen of the United States, and a resident of the town of Sterling Junction, county of 5 Worcester, State of Massachusetts, have invented new and useful Improvements in Noisemakers, of which the following is a specification.

This invention relates to improvements in 10 toys and more particularly to noisemakers.

One of the objects of my invention is to provide a simple, efficient and inexpensive device of this character designed to produce a plurality of noises.

15 Another object of my invention is to provide a simple noisemaker which may be operated to produce the noise and sounds of a horn and may also give a rattling noise.

A still further object of my invention is 20 to provide a noisemaker so designed and constructed as to assure the production of a horn as well as a rattle, the rattling noise being independent of the blast created by the horn.

25 Another important object of my invention is to enrich and amplify the intonations produced by the horn to this end assisting in making the sound coming from the horn clear and remarkably distinct.

30 Another object of my invention is to provide in a device as described a horn operated like the usual horn in combination with a sound box so constructed as to allow the air currents to expand therein and then to 35 emerge through a series of ports in a constant volume thereby considerably enriching the intonations produced in this manner.

With the above and other objects in view, 40 my invention consists in the arrangement and details of construction disclosed in the drawings and specification, and then more particularly pointed out in the appended claims.

In the drawings, wherein, similar reference characters designate similar parts throughout the respective views,

Figure 1 is a longitudinal side elevation of my invention,

50 Figure 2 is a rear end elevation thereof, Figure 3 is a top plan view of my invention,

Figure 4 is a front elevation thereof,

Figure 5 is a longitudinal sectional view taken at right angles to that of Figure 1,

Figure 6 is a cross-section through a 55 sound-box shown in Figure 1,

Figure 7 is a longitudinal sectional view of an improvement,

Figure 8 is a cross-section through the sound box shown in Figure 7, and 60

Figure 8^a is a cross-section taken at right angles to Fig. 8.

In the drawings which are merely illustrative of my invention 1 designates the tube of a horn, and 2 designates a preferably 65 wooden mouthpiece in the form of a tubular body secured with a telescoping fit upon the end of the tube 1. 3 designates the usual reed of the horn located in the end of the tube 1 where the mouthpiece fits around the 70 same. The inner chamber for the passage of air through the mouthpiece is designated 19. 4 designates the end of the mouthpiece where it projects in advance of the reed.

A sound box also serving as a rattle is 75 designated by the numeral 6 and is in the form preferably of a cylindrical sheet metal body secured edgewise to this tube 1 in such a manner that part of this body or hollow chamber projects in opposite directions from 80 the longitudinal axis of this horn. It will be seen that the body for sound box is provided with opposing flat sides. This hollow body is closed by means of the cap having a flange 8 which is secured to the body 6 with 85 a press fit. The side of this sound box or hollow chamber 6 is formed with a circular spaced apart series of air releasing or vent ports 10 substantially at a median line thereof. A series of slugs 9 are loosely mounted 90 within the sound box or hollow chamber so that when the entire instrument is agitated freely the slugs may be caused to impinge against the inner walls of the body 6 and thus produce a clear but rattling noise. This 95 adapts the sound box to also act as a rattle. The slugs 10 are inserted into the sound-box 11 before the lid or cap 7 is fastened thereon and remains permanently in position thereon. The slugs are in the form of disks or 100 may be strips or small bars so long as they are free to jump or play around so as to make a rattling sound in the sound box 6. When the cap is removed from the sound

box, then these rattling elements 9 may be introduced into the sound box.

A modification of my invention is disclosed in Figures 6, 7, 8 and 8^a. In these 5 figures I design to secure a bell within the sound box or hollow chamber in such a manner that this bell will be spaced away from the inner walls of this sound box. The bell of the concavo-convex type preferably is 10 designated 13 and the space therein is designated 16; a series of radially extending cleats or brackets 14 are provided secured respectively to the inner wall of this sound box and also to the convex portion of the bell 13, thereby properly positioning in 15 position this bell. There is a ball 15 also contained within this sound box and which loosely falls to and fro in the act of shaking or agitating this device.

20 It will thus be seen that when the device is held and shaken in a manner to allow the ball 15 to play about the bell will be rung. However by holding the horn so that the sound box is vibrated in different positions 25 the device may be used as a common rattle or as a bell ringer and in addition of course the horn may be sounded, thus producing three differentiated sounds, all pleasant.

By holding the device as shown in position 30 in Figure 3 (reference being made to the form of device shown in Figure 7) and shaking it up and down the ball 15 is almost wholly confined within the bell and falls in all positions against some portion of the bell 35 surface thus sounding prominently the bell; but by holding this same device shown in position in Figure 7 and shaking it up and down this ball 15 has a chance to engage the bell in one direction and the bottom of 40 the sound box and in this capacity serves to the best advantage to act as a rattle.

By blowing the air into and through the horn the air may be transmitted into the sound-box so as to escape through the ports 45 formed therein thus sounding the horn in the usual manner. By agitating this instrument a rattling noise may be produced.

Now as the air must escape through and from this sound box 6 to the atmosphere before the horn (which horn is imperforate) 50 is sounded to produce its blast, the ports 10 allow for this release of the air. The sound box being of a greater depth than the largest diameter of the horn the volume of air 55 blown through the tube 1 into this sound box has a chance in the latter to expand and thus to amplify the sound, producing a much clearer and richer tone, not obtainable by means of the conventional horn.

60 Numerous changes may be resorted to in practice without departing in principle from the details of construction herein disclosed.

What I claim and seek protection on is as follows:—

65 1. The combination of a horn having a

mouthpiece at one end thereof, a cylindrical hollow chamber formed integrally upon said horn at its opposite end and having an opening disposed at right angles to the longitudinal axis of said horn, and disk-shaped 70 elements introduced into said chamber so as to hold said elements against displacement, said chamber having provision for expelling air blown into said chamber from said horn.

2. In combination, a metallic horn 75 consisting, of a tube having a noisemaking part at its inner end, said horn flaring toward its outer end, a cylindrical hollow body formed integrally so as to extend diametrically beyond the flaring portion of said horn, and having a large opening at one point, slugs introduced through said large opening into said body and being sufficiently large to be confined wholly in said hollow body so as not to enter said horn, and a cap held with a 80 press fit against said hollow body so as to close its large opening.

3. A device as described consisting of a horn provided at one end with a mouthpiece, a chamber containing rattling elements, said 90 chamber being wider than said horn, disks mounted within said chamber being greater in diameter than the depth of said chamber so as to engage the walls of said chamber and each other, said chamber being carried by said horn at the outer end of said horn.

4. A device as described consisting of a horn having a mouthpiece secured at one 100 end, a cylindrical sound box formed integrally at the opposite end of said horn and formed circumferentially with a series of air ports, one of which communicates with said horn, said box being shaped so as to expand air blown thereinto from said horn, 105 and slugs contained in said sound box and designed to produce a rattling noise therein.

5. A device as described consisting of a cylindrical hollow body having opposite flat sides, one of said sides being removable so as 110 to render accessible the interior of said body, a sound producing tube having one end connected so as to communicate with the periphery of said hollow body at a point between its opposite sides, and disks of a diameter 115 greater than that of said tube and introduced into the interior of said body made accessible by the removable side.

6. As a new article of manufacture a tube, 120 a cylindrical hollow body consisting of a circular frame, of a width greater than the diameter of said tube, said body being connected to said tube so as to project in opposite directions relatively to the outer end of said tube, said frame being formed with a 125 series of air releasing ports, a plurality of disks mounted in said frame, said frame being completely closed, and a sound producing element located in said tube at its remote end from said tube.

7. In a device as described, in combination, a cylindrical hollow body having an air receiving opening therein, a noise-making tube communicating with said hollow body and passing air thereinto, a bell mounted in said hollow body out of contact with the walls thereof, and a tiny ball in said hollow body confined so as to intonate said bell.

In witness whereof he has hereunto set his hand and affixed his seal this 13 day of November, 1920.

ANTOINE L. GIRARD. [L. s.]
